UNITED STATES PATENT OFFICE.

JONATHAN E. YOUNG AND ELISHA STRONG NORTON, OF CONNEAUT, OHIO.

ELECTRICAL TRAIN SIGNALING DEVICE.

SPECIFICATION forming part of Letters Patent No. 567,211, dated September 8, 1896.

Application filed May 11, 1896. Serial No. 591,034. (No model.)

To all whom it may concern:

Be it known that we, JONATHAN E. YOUNG and ELISHA STRONG NORTON, citizens of the United States, residing at Conneaut, in the county of Ashtabula and State of Ohio, have invented certain new and useful Improvements in Electrical Train Signaling Devices; and we do hereby declare the following to be a full, clear, and exact description of the invention, such as will enable others skilled in the art to which it appertains to make and use the same.

Our invention relates to an automatic train signaling apparatus by means of which the engineer or conductor or both will be instantly informed when something has happened to the train which should be immediately investigated.

In the embodiment of the invention which is shown in the drawings and hereinafter described in detail the signal will be given when the train breaks in two or when any cock in the air-brake pipes has been tampered with and turned so as to prevent the proper action of the air-brakes or when any of the freight-car doors have been opened. A signaling-switch is also shown, whereby the conductor may signal to the engineer. The apparatus may, however, be arranged to operate when other things happen to the train or not to operate when some of the things mentioned do happen.

The invention consists in the construction and combination of parts hereinafter described and claimed.

In the drawings, Figure 1 is a diagrammatic view of a train equipped with our invention. Fig. 2 is a longitudinal vertical section of a car and the different parts of our apparatus carried thereby. Fig. 3 is a plan view of the open-circuit signaling-bell and the apparatus for closing the circuit thereof. Fig. 4 is a side view of the same, and Fig. 5 is an end-sectional view on line 5 5 of Fig. 3.

In the cab *b* of the engine *B* or in the car-boom or in both places a magneto-bell *A* is secured. This bell is connected in a normally open electric circuit supplied by battery *H*, which circuit contains the contact pieces *a' a*. In the form shown the piece *a'* is fixed, and the piece *a* is a movable spring, which will normally stand out of contact with

the piece *a'*. The relative positions of the said contact-pieces are controlled by a lever *d* or other equivalent device. In the construction shown the lever when released presses the spring *a* against the piece *a'*; but the spring *a* might be held away from the piece *a'* by the lever and might be arranged to move automatically into contact with said piece when released by said lever.

The armature *d'* of an electromagnet *D* is connected with the lever *d*, and when said magnet *D* is energized and attracts its armature the lever is held in such position that it does not force the spring *a* against the piece *a'*; but when the circuit of said magnet is broken the said lever, either by its own weight or by the spring *d*, is moved so as to press the spring *a* against the piece *a'*, and said bell sounds an alarm.

The circuit of the magnet *D* may be supplied by the battery *H* or any other battery. The circuit extends throughout the entire train or so much thereof as is equipped with the conductor-wires. The circuit is a grounded circuit, as shown, one terminal of the circuit of magnet *D* being connected with some metal part of the engine, from which it passes through the wheels to the track. The rear end of the circuit is likewise connected with the track through the trucks and wheels on the rear car.

The conductor-wires *E* pass through the air-brake pipes *G*. The said wires are insulated, but are connected with contact-pieces *e'*, (also insulated,) which may be embedded in the rubber rings *g*, which are at the ends of the metallic couplings *g* on the ends of the flexible pipes *g'*, by means of which the brake-pipes on two cars are connected, whereby said pieces *e'* will be in contact when said flexible pipes *g'* are properly coupled. The particular construction and arrangement of the connecting-piece *e'* may be varied at will. The said wires are also separated at the angle-cocks *F* in the air-brake pipe. The ends of the wires *E* are connected with springs *e e*, which bear against said cock. The part of the cock on the plane of said springs is provided with a facing *f* of hard rubber or other equivalent material. Set into this material on opposite sides of the center are two metal plates *f'*, which are connected by an insulated

- wire f^2 . When the cock is in the proper position for the air-brakes to set, the springs $e\ e$ bear against said metal plates, thereby closing the break in the circuit at this point; but when the cock has been turned into an improper position, then the said springs $e\ e$ bear against the facing f of insulating material which is set into said cocks, thereby breaking the circuit.
- 10 The hook J upon which the flexible end of the brake-pipe on the last car is suspended is connected electrically with the metallic truck of the car, and thus through the wheels with the track. The "hook," so called, is constructed in the form of a very short section of pipe closed at its inner end, but having on its outer end a coupling-piece like the coupling-pieces on the ends of the flexible pipes. When the flexible pipe-section is hung upon said hook,
- 15 the end of said pipe-section is closed thereby, so that the escape of air from the air-brake pipe at this point is prevented. One of these hooks thus constructed and connected is placed on each end of every car, wherefore the circuit may be grounded at the end of the train, whatever car chances to be the end car.
- 20 Many freight-cars have been opened and robbed after the train was made up, both while at rest and in motion, and in order that the engineer or conductor shall be notified when any car-door is opened for this or any purpose the ends of the conductor-wires E are carried out of the air-brake pipe through suitably-plugged openings, and are connected
- 25 with two metallic pieces $K\ K$, set into the door-frame, and on the door is a metallic plate K' , which, when the door is closed, touches said plates $K\ K$ and closes the break in the circuit at this point.
- 30 Of course the specific construction of the devices whereby the several breaks in the circuit of the magnet D are closed when the train is made up may be varied as much as desired without departing from the invention.
- 35 When the train is made up, the car-doors all closed, the brake-pipes all coupled together, and the cocks in said pipes all turned to the proper position, the circuit of the magnet D is continuous from one end of the train
- 40 to the other, or so far as the train is made up of cars equipped with the invention. The circuit is grounded (that is, connected with the track) at the engine and at the rear car. The magnet D therefore acts to hold the lever d in such position that the circuit of the bell is not closed thereby; but when the circuit of the magnet D is broken anywhere, either by the train breaking apart or by the uncoupling of the brake-pipes by the turning of any
- 45 of the cocks thereon or by the opening of any car-door, the lever d is immediately released, and it acts, as hereinbefore described, to force the spring a^2 into contact with the piece a' . The circuit of the alarm-bell is closed and it
- 50 rings its signal, which carries to the engineer (or conductor, or both) the information that

something has happened to the train which should be immediately investigated.

The described apparatus may also be adapted for conveying to the engineer the signals from the conductor, which are now usually transmitted by the air-whistle, wherefore the expensive mechanism with which each passenger-car is now equipped for operating this air-whistle may be dispensed with and a very much simpler and cheaper device be substituted therefor. This result is accomplished by breaking, at a convenient point in the car, the conductor-wires which have been carried out of the air-brake pipe and closing said break by a push-button switch, or other form of switch, which under normal conditions remains closed. When operated by the conductor to transmit the signal, this switch is opened, thereby breaking the signaling-circuit and producing the same result, heretofore described, which occurs when the train breaks apart or any of the other things happen which have been heretofore mentioned.

Having described our invention, we claim—

1. In a train signaling apparatus, the combination of an electrical signaling device at one end of the train, the insulated conductor-wires inclosed within the air-pipes extending from car to car, and separated at every air-cock in the air-pipes, with the air-pipes, the air-cocks therein, and switches, operated by said air-cocks and wholly inclosed within said air-pipes, for closing the breaks in said conductor-wires, substantially as and for the purpose specified.

2. In a train signaling apparatus, the combination of an electric signal, in a normally open circuit, an automatic device for closing said circuit, an electromagnet, preventing the action of said device, connected in a circuit extending from one end of a train to the other end, having a single conductor-wire which is inclosed in, but insulated from, the air-pipes and is broken at every air-cock in said pipes, with the air-pipes, the air-cocks therein, and switches inclosed within the air-pipes and operated by said air-cocks for closing the breaks in said conductor-wire, the said circuit being connected at its terminals with the metal parts of the running-gear whereby the circuit is grounded, substantially as and for the purpose specified.

3. The combination of a railway-train, the air-brake pipes of the several cars having flexible ends, the conductor-wires of a continuous electrical circuit contained in said air-brake pipes, and connected with the metallic coupling-pieces on the flexible ends of the air-brake pipes of the several cars, coupling-hooks on the several cars for suspending the flexible ends of the air-brake pipes and closing the ends of said pipes, electrical connection between said hooks and the car-wheels, whereby the train-circuit may be grounded at the rear end of the train, with a magneto-bell connected in a normally open

circuit, two separable contact-pieces in said circuit, a device for controlling the relative positions of said contact-pieces, an electromagnet connected in the train-circuit, its armature which is connected with said controlling device, and an electrical connection between the wires of the train-circuit and the wheels on opposite sides of the battery to the rear grounding connection between the hook 5 and wheels, substantially as and for the purpose specified.

4. The combination of a railway-train, the air-brake pipes of the several cars, a conductor-wire passing through each air-brake 15 pipe and connected at its ends with the metallic couplings on the ends of said air-brake pipes, said wires being broken at the cocks in said air-brake pipe, the said cocks having insulating-strips, whereby the ends of said wires 20 may be electrically connected or disconnected by the said cocks, the said wires being extended out of said pipes and broken, contact-

pieces on the car-doors and their frames for electrically connecting the said broken wires, the circuit formed by said wires being connected at opposite ends thereof with the ground through the metal part of the running-gear, a magneto-bell connected in a normally open circuit, a device for controlling the relative position of said contact-pieces, an 25 electromagnet connected in the train-circuit, and its armature which is connected with said controlling device, substantially as and for the purpose specified.
